UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL CASTING MACHINE.

Application filed October 22, 1918. Serial No. 259,175.

To all whom it may concern:

Be it known that I, DAVID S. KENNEDY, a citizen of the United States, residing at Brooklyn, in the county of Kings and State 5 of New York, have invented certain new and useful Improvements in Typographical Casting Machines, of which the following is a specification, reference being had thereto in to the accompanying drawing.

10 My invention relates to typographical casting machines, such as linotype machines of the general organization represented in U. S. Letters Patent to O. Mergenthaler, No. 436,532, wherein circulating matrices 15 are released from a magazine in the order in which their characters are to appear in print and then assembled in line, the composed line transferred to the face of a mold, the mold filled with molten metal to form 20 a slug or linotype against the matrices which produce the type characters thereon, and the matrices thereafter returned through a distributing mechanism to the magazine from which they started.

25 In ordinary practice, when the composed line is transferred to the mold, the matrices thereof stand in perpendicular or rectilinear relation thereto. My present invention is intended primarily to adapt the machine 30 so that the matrices may be presented to the mold in inclined position also. To that end I have devised certain improvements in the casting and justifying devices, as well as in other parts of the machine as subsequently 35 described and claimed.

In the accompanying drawings, I have shown my invention merely in preferred form and by way of example, and as applied to a linotype machine of the general 40 class stated, but obviously there are various other embodiments and adaptations which will still be comprised within its spirit. Thus, for instance, it is applicable to all forms of typographical casting machines, whether the product thereof be linotypes, logotypes, or single types or dies. Generally speaking, I desire it to be understood that I do not limit myself to any specific form or embodiment, except in so far 45 as such limitations are specified in the claims.

Referring to the drawings:

Fig. 1 is a front view of a portion of a

linotype machine, with my invention embodied therein;

55 Fig. 2 is a similar view of a portion of the casting mechanism with the vise frame removed;

Fig. 3 is a section on the line 3—3 of Fig. 2;

60 Fig. 4 is a detail on the line 4—4 of Fig. 2;

Fig. 5 is a section on the line 5—5 of Fig. 4;

65 Fig. 6 is a section on the line 6—6 of Fig. 2;

Fig. 7 is a section on the line 7—7 of Fig. 2;

Fig. 8 illustrates a variety of italic matrices now in general use;

70 Fig. 9 shows a different form of italic matrices; and

Fig. 10 is a perspective of a single matrix.

Referring to Fig. 1, the matrices and spacers are delivered one by one to the assembler A. When the group or line is composed, the assembler is elevated and the line is transferred through the intermediate channel B to the dotted line position D when it is received by the first elevator C. The first elevator then descends and presents 80 the line in the casting position generally indicated at D¹. After the cast is made, the first elevator lifts the matrices and spacers to the dotted line position D², from which they are shifted to the upper transfer channel 85 and second elevator and are subsequently returned to their original places of storage in the usual manner.

Referring also to Figs. 2 and 3 it is noted that in the casting position the line of ma-

90 trices and spacers is confined at its ends between the jaws F and G, which in normal operation have their faces in vertical position, as indicated by dotted lines in Fig. 2.

The mold disk E¹ then moves laterally to 95 bring the mold E at one side into close relation to the matrices, and similarly the pot mouth E² advances into close relation to the mold at its other side, after which the molten metal is injected in the usual manner.

Prior to the casting operation the line is 100 both aligned and justified, the aligning action being effected by a slight upward movement of the first elevator C, and the justify-

105 ing action being effected by the upward movement of the justifying slide K, mounted

on the rods K^1 and K^2 , which serves to force the wedge spacers through the line and to extend it between the jaws F and G.

The devices and their functions as so far described are or may be substantially the same as those in the ordinary commercial linotype machines, except in so far as subsequently pointed out.

As previously stated, when the matrices 10 are presented to the mold in ordinary practice, they occupy a rectilinear or perpendicular relation thereto, and this is generally the case even though the characters thereon be italics or other inclined characters.

15 For instance, Fig. 8 shows the usual form of italic matrices Z, it being noted that the characters Z¹ thereon are inclined with relation to the sides of the matrices. It is frequently desired to employ a different style of 20 italic character, which will lie more closely together and so that adjacent characters will overhang, i. e., will overlap a line drawn vertically between them, which features are not secured by the matrices Z shown in Fig. 8.

25 Therefore, it is proposed to use the style of matrix or matrix bar X shown in Figs. 9 and 10, wherein the italic characters or character impressions X¹ are more nearly parallel to the sides of the matrices, and are arranged thereon for alignment in an inclined position of the matrices, and the overlying or overhanging effect is obtained by inclining the matrices themselves from the vertical in substantially the relation indicated 30 in Fig. 9. In another aspect, the characters or character impressions X¹ may be said to be inclined with respect to the parallel sides of the matrices or matrix bars, since the base lines of such characters are disposed 35 at an inclination to the sides of the matrices.

40 In other words, when viewed from the standpoint of their major axes, the characters X¹ may be regarded as extending parallel to the sides of the matrices; whereas, when viewed 45 from the standpoint of their minor axes, said characters may be regarded as extending at an inclination to the parallel sides of the matrices. In either case, the characters are arranged on the matrices so as to be brought 50 into alignment when the matrices are located in the proper inclined position. In order to secure the correct alignment of the matrices X, their ears X² and X³ are cut away or inclined on their lower and upper 55 surfaces respectively to conform to the general inclination of the matrices, as best shown in Fig. 9, and there contrasted with the rectilinear form of the ears Z² and Z³ of the matrices Z shown in Fig. 8. When in 60 casting position, the matrices X (being of the head letter variety) are supported in the first elevator C by their upper ears X², which rest upon the usual sustaining rails C¹ of the elevator (Fig. 3), the lower ears 65 X³ of the matrices on their mold contact-

ing edges being engaged with the overlying mold aligning lip or ledge e, which engagement takes place as the elevator rises in effecting the alignment of the matrices preparatory to the casting operation as before 70 explained. Since the upper ears X² are cut away or inclined at their lower ends and the lower ears X³ are cut away or inclined at their upper ends, the matrices are free to be tilted laterally to bring their characters 75 into proper alignment. When so tilted the matrices turn or rock individually about their upper supporting ears X² as pivots, and this rocking movement of the matrices not only places the lower ends of said upper ears in horizontal alignment for surface contact with the elevator rails C¹, but also brings the upper ends of the lower ears X³ into horizontal alignment for surface contact with the mold aligning lip or ledge 80 e, thereby insuring the perfect alignment 85 of the matrix characters.

In order to effect the inclination of the matrices X in the casting position, I preferably employ the inclined jaws F and G, best 90 shown in full lines in Fig. 2, and it will be apparent that the desired position of the matrices will be imparted thereto by their delivery between the jaws by the first elevator C, entirely irrespective of their position 95 prior to that time. In other words, the matrices may be composed in the assembling elevator A in their customary vertical condition being supported therein by their lower ears, whose right-angular bottom surfaces 100 rest upon the usual sustaining rails, and will consequently receive the necessary change of position by reason of their delivery between the inclined jaws. Moreover, in the form shown, I have made the 105 jaws F and C pivotally movable, so that they may be adjusted either to vertical or inclined position. In this way the machine is readily adapted at the will of the operator to handle either the regular form of 110 composed line, wherein the matrices are in rectilinear or perpendicular relation to the mold, or the special form of line, wherein the matrices are to be in inclined relation to the mold. Further, due to this adjustability 115 of the jaws, the matrices may, if desired, be delivered between them in vertical position and then be turned to inclined position by merely moving the jaws about their pivots.

To secure these results, the jaws are arranged in the form shown in Fig. 2. The jaw F (see also Fig. 7) is pivotally mounted at F¹ on the plate H, and is provided with a spring-pressed plunger F² adapted to engage one or the other of two locking depressions 125 H² formed in the plate, so as to hold the jaw in either its vertical or inclined position. The jaw is also provided with a stop F³ projecting into a recess H³ in the plate to limit its movement in opposite directions. Simi- 130

larly, the jaw G (see also Fig. 6) is pivotally mounted at G¹ on the plate J, it being retained thereon by the nut J¹, and is provided with a spring-pressed plunger G³ adapted to engage either with or at one side of the projection J² on the plate, so as to hold the jaw in either its inclined or vertical position. In order to limit the movement of the jaw in opposite directions, it is formed with a recess G² surrounding the projection J². This construction permits the ready manual adjustment of the jaws so as to adapt the machine in the manner previously indicated.

As best shown in Fig. 2, the inclination of the composed line necessarily involves the corresponding inclination of the wedge spacers Y which are forced upward through the line by the justifying slide K. In order to prevent the breaking or bending of the wedges when in this position, it is desirable to modify correspondingly the action thereon of the justifying slide. To this end I provide the slide with a relatively movable member L, which is held in normal position by the compression spring L¹ acting against the projecting stud L² thereon. In ordinary operation, when the spacers are perpendicular to the mold, the member L acts upon them in the usual manner; but when the spacers are inclined, the member L is moved laterally with relation to the slide K so that its justifying action is in the direction of the inclination of the wedges. This I preferably effect by the employment of the piece M formed with a cam surface corresponding to the inclination of the spacers and adapted to engage the end of the member L, so that as the justification slide rises the member L is shifted laterally and the resultant effect is to force the spacers through the line in the direction of their inclination.

The cam piece M is manually adjustable to either the full line or dotted line position shown in Fig. 2. In the latter, it is inactive and the justifying slide acts in the regular way upon the spacers in perpendicular relation to the mold. The cam piece M is slidably mounted in the frame piece M¹, and its shank M⁵ (see also Figs. 4 and 5) carries the adjusting rod M², which is capable of a limited rotary motion with reference thereto. The rod M² is formed at its inner end with a locking piece M³ adapted in its inactive position to be turned down into the recess M⁴ in the shank M⁵, and in its active position to be turned upwardly to engage the frame when the cam piece is in operative relation to the member L. In this way, by the manipulation of the rod M², the cam piece may be moved inward and locked so as to provide the inclined action of the justifying member L, or may be retracted to inactive position to permit the ordinary vertical movement thereof.

As previously stated, I have shown my in-

vention merely in preferred form and by way of example, and obviously many changes and alterations therein will suggest themselves to those skilled in the art without departure from its scope.

Having thus described my invention, its construction and mode of operation, what I claim and desire to secure by Letters Patent of the United States, is as follows:

1. In a typographical machine equipped with circulating matrices formed with characters arranged thereon for alignment in an inclined position of the matrices, the combination of casting mechanism including a mold, devices for composing a group or line of matrices, and automatic means for presenting the composed line to the mold with the matrices in proper inclined relation thereto.

2. In a typographical casting machine equipped with matrices formed with characters arranged thereon for alignment in an inclined position of the matrices, the combination of casting mechanism, devices for composing the matrices in group or line, and automatic means for effecting the proper inclination of the matrices before the casting operation.

3. In a typographical machine equipped with matrices formed with characters arranged thereon for alignment in an inclined position of the matrices, the combination of devices for composing the matrices in group or line, and means for subsequently tilting the matrices in said line or group to bring their characters into proper alignment.

4. In a typographical casting machine equipped with matrices formed with characters arranged thereon for alignment in an inclined position of the matrices, the combination of devices for composing the matrices in group or line, casting mechanism including a mold, means for transporting the composed group or line to the mold, and means for effecting the proper inclination of the matrices before the casting operation.

5. In a typographical machine equipped with matrices formed with characters arranged thereon for alignment in an inclined position of the matrices, the combination of casting mechanism including a mold, means for transferring a group or line of matrices thereto, and a pair of jaws supported in the machine frame and arranged to engage said group or line during casting, the said jaws having their matrix engaging faces inclined so as to hold the matrices in proper inclined relation to the mold.

6. In a typographical machine equipped with matrices formed with characters arranged thereon for alignment in an inclined position of the matrices, the combination of casting mechanism including a mold, devices

- for composing the matrices in group or line, means for transferring the composed group or line to the mold, and means for altering the positions of the matrices in the group or line to present them in proper inclined relation to the mold.
7. In a linotype machine equipped with matrices formed with characters arranged thereon for alignment in an inclined position of the matrices, the combination of an assembler wherein the matrices are composed in vertical position, casting mechanism including a mold, devices whereby the matrices are transferred from the assembler to the casting mechanism and means whereby the matrices are presented to the mold in proper inclined position.
8. In a typographical machine equipped with matrices formed with characters arranged thereon for alignment in an inclined position of the matrices, the combination of casting mechanism including a mold, means for transporting a composed line of matrices to the mold, and a pair of jaws supported in the machine frame and arranged to hold said group or line of matrices in casting position, the said jaws having their matrix engaging faces inclined so that the matrices will be presented to the mold in proper inclined relation thereto.
9. In a typographical machine comprising casting mechanism, the combination of a mold and a pair of jaws to hold a group or line of matrices in casting position, the said jaws being adjustable so that the matrices may be presented to the mold in either perpendicular or inclined relation thereto, with means for positively holding the jaws in their adjusted position.
10. In a linotype machine comprising casting mechanism, the combination of the mold E and the confining jaws F and G, the said jaws being pivotally mounted so as to hold the matrices in either perpendicular or inclined relation to the mold, with means for positively holding the jaws in their adjusted position.
11. In a linotype machine, the combination of devices to confine a matrix group or line containing justifying spacers in inclined position therein, and justifying means to advance the spacers in the group or line, said means being arranged to move laterally to adapt their action to the inclined position of the spacers.
12. In a linotype machine, the combination of devices to confine a matrix group or line containing justifying spacers in inclined position therein, and justifying means to advance the spacers in the group or line, said means acting in an inclined direction corresponding to the position of the spacers.
13. In a linotype machine, the combination of devices to confine a matrix group or line containing justification spacers in inclined position therein, and a justifying slide to advance the spacers in the group or line, the contacting portion of the slide being constructed to move laterally relative to the slide as the latter advances.
14. In a linotype machine, the combination of devices to confine a matrix group or line containing justifying spacers in inclined position therein, a justifying slide to advance the spacers in the group or line, a member of said slide being constructed to move laterally, and a device to effect said lateral movement as the slide advances.
15. In a linotype machine, the combination of devices to confine a matrix group or line containing justifying spacers in inclined position therein, a justifying slide to advance the spacers in the group or line, a member of said slide being constructed to move laterally, and a device to effect said lateral movement as the slide advances, the latter device being adjustable so as to be rendered operative or inoperative at the will of the operator.
16. In a linotype machine, the combination of devices to confine a matrix group or line containing justifying spacers in inclined position therein, and the justifying slide to advance the spacers in the group or line, comprising a laterally movable member, with a cam piece to engage and move the member laterally as the slide advances.
17. In a linotype machine, the combination of devices to confine a matrix group or line containing justifying spacers in inclined position therein, and the justifying slide to advance the spacers in the group or line, comprising a laterally movable member with a cam piece to engage and move the member laterally as the slide advances, the cam piece being adjustable so as to be rendered operative or inoperative at the will of the operator.
18. In a typographical machine equipped with matrices formed with characters arranged thereon for alignment in an inclined position of the matrices, the combination of casting mechanism including a mold, and mechanism for composing the matrices in group or line and presenting the composed group or line to the mold with the matrices in proper inclined position.
19. In a typographical machine equipped with matrices formed with characters arranged thereon for alignment in an inclined position of the matrices, the combination of casting mechanism including a mold, means for presenting the matrices thereto in proper inclined position and means for distributing the matrices after the casting operation.
20. In a typographical machine equipped with matrices formed with characters arranged thereon for alignment in an inclined position of the matrices, the combination of means for composing the matrices in

group or line in vertical or upright position, means for subsequently inclining the matrices to bring their characters into proper alignment, and means for casting a slug 5 from the composed group or line in the inclined condition of the matrices.

21. In a typographical machine equipped with matrices formed with characters arranged thereon for alignment in an inclined position of the matrices, the combination of means for composing the matrices in group or line in vertical or upright position, means for subsequently inclining the matrices to bring their characters into proper alignment, means for casting a slug from the composed group or line in the inclined condition of the matrices, and means whereby said matrices are restored to up-right condition after the casting operation. 10 22. In a typographical machine equipped with matrices formed with supporting surfaces arranged at inclinations to the longitudinal planes of the matrices, the combination of means for composing the matrices in group or line, casting mechanism including a mold, means for transporting the composed group or line to the mold and including a sustaining rail upon which the supporting surfaces of the matrices rest, and 15 means for rocking or tilting the matrices upon said sustaining rail before casting to locate them in proper inclined relation to the mold.

23. In a typographical machine equipped with matrices formed with supporting surfaces and alineing surfaces arranged at inclinations to the longitudinal planes of the matrices, the combination of means for composing the matrices in group or line, casting mechanism including a mold provided with an aligning lip or ledge, means for transporting the composed group or line to the mold and including a sustaining rail upon which the supporting surfaces of the matrices rest, and means for rocking or tilting the matrices upon said sustaining rail before casting to locate them in proper inclined relation to the mold. 20

24. A linotype matrix formed with a supporting ear, the said ear having one end arranged at an inclination to the longitudinal plane of the matrix, for the purpose described.

25. A linotype matrix formed at its upper end and on opposite edges with supporting ears, the said ears having their lower ends arranged at an inclination to the longitudinal plane of the matrix for the purpose described. 25

26. A linotype matrix formed with a mold contacting or aligning ear, the said ear having one end arranged at an inclination to the longitudinal plane of the matrix, for the purpose described.

27. A linotype matrix formed at its lower

end with a mold contacting or aligning ear, the said ear having its upper end arranged at an inclination to the longitudinal plane of the matrix, for the purpose described.

28. A linotype matrix formed with a supporting ear and a mold contacting or aligning ear, each of said ears having one end arranged at an inclination to the longitudinal plane of the matrix, for the purpose described. 70

29. A linotype matrix formed with a supporting ear and a mold contacting or aligning ear, the supporting ear having its lower end and the aligning ear its upper end arranged at an inclination to the longitudinal plane of the matrix, for the purpose described. 75

30. A linotype matrix formed at its upper end with a pair of supporting ears and at its lower end with a mold contacting or aligning ear, the supporting ears having their lower ends and the aligning ear its upper end arranged at an inclination to the longitudinal plane of the matrix, for the purpose described. 80

31. In a linotype machine, the combination with a mold, of means for assembling a line of matrices and for automatically positioning the assembled matrices at the mold in oblique positions transversely of the mold for the casting of italics. 90

32. In a linotype machine, the combination with a mold, of vice jaws associated with the mold and having matrix engaging faces that are oblique to the mold, and a space band justification bar having space band driving surfaces arranged to move parallel to the oblique face of said jaws, in the space band driving action. 100

33. In a method of casting italic type-faces on slugs or type-bars, the steps which consist in assembling in a vertical position a plurality of matrix bars carrying suitable character impressions, then inclining such assembled body of matrix bars, and casting such slug thereupon. 105

34. In typograph mechanism, a matrix bar having parallel sides and a character impression inclined with respect to such sides, said bar being provided with means for aligning same at different angles. 115

35. In typograph mechanism, a matrix bar having parallel sides and a character impression inclined with respect to such sides, said bar being provided with means for aligning same at right angles to such sides and at an angle corresponding with the inclination of such character impression. 120

36. In typograph mechanism, the combination with a plurality of matrix bars having parallel sides and character impressions inclined with respect to such sides, of means adapted to assemble said bars in line normal to such line, and other means adapted to re- 125 130

tain said bars in line inclined at an angle to such line corresponding with the inclination of such character impressions.

37. In typograph mechanism, the combination with a plurality of matrix bars having parallel sides and character impressions inclined with respect to such sides, of guide means adapted to engage and retain said bars in line, said bars being formed with engaging elements whereby they may be thus retained either normal to such line or at an angle thereto, as desired.

38. In typograph mechanism, the com-

bination with a plurality of matrix bars having parallel sides and character impressions inclined with respect to such sides, of guide means adapted to engage and retain said bars in line, said bars being formed with engaging elements whereby they may be thus retained either normal to such line or at an angle thereto, as desired, and means adapted to clamp said bars together and incidentally tilt same to such angle.

In testimony whereof, I have affixed my signature hereto.

DAVID S. KENNEDY.
